UNITED STATES PATENT OFFICE.

CLAUDE REES AND CHARLES F. HINE, OF SAN FRANCISCO, CALIFORNIA.

DRYING APPARATUS.

Application filed October 22, 1924. Serial No. 745,148.

To all whom it may concern:

Be it known that we, CLAUDE REES and CHARLES F. HINE, citizens of the United States, and residents of the city and county 5 of San Francisco, State of California, have invented a certain new and useful Drying Apparatus, of which the following is a specification.

The invention relates to a drying apparatus for drying, dehydrating or partially dehydrating materials such as fruits, vegetables and other products which require drying to place them in condition for use or sale.

15 An object of the invention is to provide a simple form of drying apparatus having a relatively small capacity.

Another object of the invention is to provide a drying apparatus through which air or other drying medium is circulated by a 20 single blower.

Another object of the invention is to provide a drying apparatus having means intermediate the discharge and the inlet of 25 the blower, for mixing or agitating the air or drying medium to overcome the effect of stratification, due to the heating of the air.

Another object of the invention is to provide a drying apparatus in which the direction of the flow of air with respect to the materials being dried may be reversed without reversing the direction of the flow 30 of air.

35 A further object of the invention is to provide a drying apparatus of small capacity in which the material to be dried is arranged in trays which are disposed in tiers and in which the material in the upper and 40 lower trays of the tier are subjected to substantially the same drying effect.

45 A further object of the invention is to provide a drying apparatus in which the tiers of trays are rotatably mounted, so that the positions of the tiers may be reversed.

The invention possesses other advantageous features, some of which with the foregoing, will be set forth at length in the following description where we shall outline 50 in full that form of the apparatus of our invention which we have selected for illustration in the drawings accompanying and forming part of the present specification. In said drawings we have shown two forms 55 of drying apparatus embodying our inven-

tion, but it is to be understood that we do not limit ourselves to such form, since the invention, as set forth in the claims, may be embodied in a plurality of other forms.

Referring to said drawings:

Figure 1 is a horizontal section taken through a drying house embodying our invention, directly below the roof of the house.

Figure 2 is a cross section of the house taken on the line 2—2 Figure 1, a portion 65 of the structure being broken away to further disclose the construction.

Figure 3 is a detail of one of the turn tables forming part of the dryer.

Figure 4 is a vertical cross section through 70 the turn table shown in Figure 3.

Figure 5 is a horizontal section through a modified form of drying house embodying our invention.

Figure 6 is a side elevation of one of the 75 tiers of trays and;

Figure 7 is an end elevation of one of the tiers of trays and the adjacent portion of the house.

The drying apparatus of our invention 80 comprises a house or other enclosing structure into which the material to be dried is introduced. The material is preferably arranged on trays and the trays arranged in tiers, the trays being constructed to permit 85 the passage of air between the successive trays in the tier, for the purpose of drying the material disposed on the trays. The house is preferably divided into two elongated compartments and air is circulated 90 by a blower through the two compartments in succession, the blower being arranged at one end of the house so that it receives air from one end of one compartment and discharges the air into the adjacent end of the 95 other compartment. The air then passes down through one compartment and back through the other compartment to the intake of the blower. A tier of trays is arranged in each compartment so that the 100 air passes through the two tiers successively.

The air discharged by the blower is preferably heated before it passes through the first tier and, in passing through this tier and discharging therefrom, it becomes stratified, 105 the warmer air passing to the top and the cooler air settling to the bottom. If this stratified air were permitted to pass through the second tier, the material in the upper trays would be dried to a much greater ex- 110

tent than the material in the lower trays. To overcome this deleterious effect, we have provided, within the house, between the two tiers of trays, a device for mixing or swirling the air, so that the air entering the second tier enters in a uniform stream. The blower operates to produce a current of air through the house in one direction, but it is advisable in the proper drying of some material such as fruit and vegetables, that the direction of the flow of air with respect to the material be reversed, so that the material at both sides of the tray will be equally dried. To accomplish this result, we have provided means for reversing or rotating the tiers through an angle of 180 degrees so that the direction of the flow of air with respect to the trays is reversed. The tiers are reversed at suitable intervals, so that all of the material is subjected to substantially the same drying effect. The reversal of the tiers is preferably accomplished by the provision of turn tables upon which the tiers are disposed, so that the tiers may readily be rotated through angles of 180 degrees. In order to overcome the necessity of greatly increasing the house, to take care of the swing of the tiers as they are rotated, we have provided an aperture in the partition dividing the house into two compartments, and have provided closing strips for closing the space between the edges of the tiers and the edges of the partition to prevent the flow of air around the tiers.

Any desirable means may be employed for heating the air and in the drawings we have shown a radiator through which the air passes before it enters the passages in the first tier. The radiator is heated by the combustion of fuel and this heat is conducted to the air as it passes through the radiator.

Referring particularly to Figures 1 and 2, the drying apparatus comprises a house or other enclosing structure 2 having large doors 3 in its side walls, to permit the introduction of and removal of tiers of trays from the house. The tiers of trays are preferably arranged on trucks 4, movable on tracks 5 which extend transversely through the house to permit the ready introduction and removal of tiers of trays.

The house is divided into two compartments 6 and 7 by the longitudinally extending partition wall 8, which is interrupted at that portion of the house through which the tracks 5 pass, to permit the trucks with their tiers of trays to be passed transversely through the house when desired. The trays are preferably formed with substantially impervious bottoms and are provided with side walls 12 which extend upward above the end walls 13 so that when the trays 14 are arranged in tiers, a horizontal passage is provided between each two successive trays.

Each tier thus comprises a plurality of superposed layers of material, spaced apart by horizontal passages through which the air passes. The side walls 12 of the successive trays are in contact, so that the air may only pass longitudinally through the tier of trays, the successive side walls 12 of the superposed trays forming a substantially solid side wall of the tier. The air is circulated through the compartments 7 and 6 successively and consequently through the tiers 15 and 16 in the two compartments successively. To prevent the air from passing through the spaces between the edges of the tiers and the partition wall 8 and the side walls of the house, movable shutters are arranged to close these spaces, so that substantially all of the circulating air is directed through the horizontal passages in the tiers. The side walls of the house are provided at the sides of the doors 3 with inward extensions 17 which terminate adjacent the path of movement of the edges of the tiers, when the tiers are rotated. The partition 8 is similarly provided with a short cross partition 18 at opposite sides of the opening in the partition 8, and the ends of the short partition 18 terminate adjacent the path of the edges of the tiers. Pivoted to the projections 17 are shutters 21 which are movable into contact with the sides of the tiers to prevent the passage of air through the spaces. Similarly, shutters 22 are provided at the ends of the partition 18 to close the spaces existing at those points and the shutters 22 are provided with rods 23 which extend to the side walls of the house, so that the shutters may be opened and closed while the tiers of trays are in position. During the drying operation the shutters are in position to close the gaps between the tiers and the house structure, and when it is desired to remove or rotate a tier, the shutters are moved back.

Means are provided for permitting rotation of the tiers and preferably comprise turn tables 24 arranged within the house in the path of the transverse rails 5. In the construction shown in Figure 1 I have provided two turn tables spaced apart a sufficient distance to permit rotation of the tiers of trays arranged thereon. The turn tables are provided with tracks which are aligned with the tracks 5 so that the trucks 4 may be readily run onto and off of the turn tables. The upper surface of the turn table is flush with the floor of the house and the turn table is mounted on rollers 25 so that it may be readily rotated. A bolt 26 is associated with each turn table for the purpose of holding it in position with the tracks thereon aligned with the tracks 5. By withdrawing the bolt 26, the turn table may be rotated to reverse the position of the tier in the house, so that the direction of flow of air with respect to the trays in the tier

is reversed, thereby permitting the material on both sides of the center of the tray to be evenly dried. In the construction shown in Figure 5, the turn tables 24 are disposed outside of the house and when it is desired to reverse the position of the tier, the truck carrying the tier is moved from the house onto the turn table, then turned around and then replaced in the house. With this arrangement the house may be made slightly narrower than when the construction shown in Figure 1 is employed, and when desirable, only one turn table need be provided, but this will require removing both tiers from the house when it is desired to reverse the position of the tier which is remote from the turn table.

Means are provided for circulating air through the house and through the two tiers of trays in series. Arranged adjacent one end of the compartment 6 is a blower 31 driven by the motor 32 and having its inlet opening into the compartment 6. The main discharge conduit 33 of the blower opens into the adjacent end of the compartment 7, preferably at the top thereof. The blower is also provided with a secondary discharge conduit 34 opening to the atmosphere, so that a portion of the air passing through the blower, is discharged outside of the house. By this arrangement, the major portion of the air is recirculated and a portion of the air is continuously exhausted. This causes the humidity of the air to remain substantially constant and provides for the discharge from the house of the excess moisture which is taken up by the air.

Means are provided for agitating or swirling the air discharged from the blower so that it will not remain adjacent the ceiling 35 of the house but will be evenly distributed throughout the whole cross section of the house. This means comprises a deflecting plate or swirling plate 36 arranged in the compartment 7 adjacent the discharge conduit 33 of the blower, and as the air discharges from the blower it contacts with the deflecting plate 36 and is directed downward toward the bottom of the house and is again directed upward by the second deflecting plate 37. This causes a swirling and mixing of the air so that a substantially homogeneous mixture of the air is provided. Arranged adjacent the swirling plate 36 is a heater, comprising a radiator consisting of a plurality of vertically disposed tubes 40 connected at the bottom and top to the headers 38 and 39 respectively. The header 39 is connected to the stack 42. Gases of combustion from the furnace or combustion chamber 43 pass through the conduits 44 and 45 into the header 38 whence they pass through the tubes 40, heating the tubes. The air being circulated through the house, passes through the heater and is heated

thereby. In order to straighten out the swirling movement of the air and to cause the air to pass through the compartment 7 in a substantially uniform stream, a perforated plate 46 is disposed in front of the heater. The eddies and swirls are removed from the air as it passes through the plate 46, so that the air moves in substantially a straight line through the tier 15 arranged in the compartment 7.

In passing through the tier 15 and in discharging therefrom, the air has a tendency to become stratified, the warmer air rising to the top and the cooler air settling to the bottom. From the compartment 7 the air passes around the end of the partition 8 at the far end of the house, into the compartment 6 and passes back through the compartment 6 to the inlet of the blower 31, passing through the tier 16 of trays in its progress through the compartment 6. In order to prevent uneven drying of the material in the upper and lower trays in the tier 16, due to the stratification of the air, means are provided for agitating or mixing the air before it reaches the tier 16, so that a substantially homogeneous stream of air is directed through the tier 16. This is accomplished by causing the air to pass in contact with a swirling or deflecting plate in its movement from the tier 15 to the tier 16, so that stratification of the air is eliminated.

Arranged in the opening in the partition 8 at the far end of the house, is an upwardly inclined deflecting plate 51 which inclines upward from the floor of the compartment 7 to adjacent the ceiling in the compartment 6. The air passing from one compartment to the other is therefore discharged into the compartment adjacent the upper portion thereof. Arranged in the end of the compartment 6 adjacent the air discharge end of the deflecting plate 51, is a curved deflecting plate 52 which deflects the air stream downward into the substantially semi-circular deflecting plate 53. In passing in contact with the deflecting plates 52 and 53, the air is swirled and thoroughly mixed, so that substantially all stratification thereof is removed and so that the air passes to the tier 16 in a substantially homogeneous, uniform stream. After passing through the tier 16, the air passes to the inlet of the blower 31, by which a portion of the air is recirculated and a portion discharged from the house.

The blower 31 is driven by the motor 32, which is arranged in an extension 54 of the house, in which the furnace or combustion chamber 43 is also preferably arranged. The furnace shown in the drawings is adapted to the combustion of liquid fuel and a compressor 55 is provided for furnishing air to atomize the fuel.

In the drawings we have shown the invention applied to a drying apparatus con-

structed to accommodate two tiers of trays, but it is to be understood that we do not limit ourselves to an apparatus which is capable only of accommodating two tiers 5 of trays, since the arrangement of the house may readily be modified to accommodate a greater or a lesser number of tiers.

We claim:

1. A drying apparatus comprising a house 10 adapted to receive the material to be dried, a blower for circulating air through the house, means for swirling the air discharged by the blower, means for heating the air and means for swirling the air as it passes 15 through the house.
2. A drying apparatus comprising a house adapted to receive the material to be dried, a blower for circulating air through the house, means adjacent the blower discharge 20 for heating the air, and means in the house intermediate the blower discharge and the blower inlet for swirling the air passing through the house.
3. A drying apparatus comprising a house 25 adapted to receive the material to be dried, a blower having an inlet opening into the house, a blower discharge opening into the house, a secondary blower discharge opening outside the house, means for heating the air 30 discharged into the house by the blower and stationary means within the house for swirling the circulating air.
4. A drying apparatus comprising a house adapted to receive the material to be dried, 35 a blower for circulating air through the house, means for heating the air and means interposed between the blower discharge and the heating means for causing the air to flow in a uniform stream.
- 40 5. A drying apparatus comprising a house adapted to receive the material to be dried, a blower for circulating air through the house, means for heating the air, means adjacent the blower discharge for swirling the 45 discharged air and means for converting the swirling air to a uniform air stream.
6. A drying apparatus comprising a house adapted to receive the material to be dried, a partition dividing the house into two 50 compartments, a blower having an inlet opening into one compartment and a discharge opening into the other compartment, an air heater in the latter compartment adjacent the blower discharge and means in 55 the house for mixing the circulating air during its passage through the house.
7. A drying apparatus comprising a house adapted to receive the material to be dried, a partition dividing the house into two compartments, a blower arranged adjacent one 60 end of the house having an inlet opening into one compartment and a discharge opening into the other compartment whereby air is circulated through the house, means for heating 65 the circulating air, said heating tending

to cause stratification of the air and means at the other end of the house for mixing the air.

8. A drying apparatus comprising a house adapted to receive the material to be dried, 70 a partition dividing the house into two compartments, a blower arranged adjacent one end of the house having an inlet opening into one compartment and a discharge opening into the other compartment whereby air 75 is circulated through the house, means for heating the circulating air, said heating tending to cause stratification of the air, a passage connecting the compartments at the other end of the house and means adjacent 80 said passage for mixing the circulating air.

9. A drying apparatus comprising a house adapted to receive the material to be dried, a partition dividing the house into two compartments, a blower arranged adjacent one 85 end of the house having an inlet opening into one compartment and a discharge opening into the other compartment whereby air is circulated through the house, means for heating the circulating air, said heating tending to cause stratification of the air, a 90 passage connecting the compartments at the other end of the house and deflecting means arranged adjacent the passage for mixing the circulating air.

10. A drying apparatus comprising a house, two tiers of trays in said house for the material to be dried and arranged with a horizontal passage above the layer of material in each tray, means for blowing air 100 through the two tiers of trays successively, means for heating the air and stationary air swirling means through which the air travels between the trays.

11. A drying apparatus comprising a 105 house, two tiers of trays arranged side-by-side in said house for the material to be dried, said trays being arranged to permit passage of air through the tiers in a longitudinal direction only, means for circulating 110 the air through the house so that the air passes in opposite directions longitudinally through the two tiers and means for heating the air.

12. A drying apparatus comprising a 115 house, two tiers of trays arranged side-by-side in said house for the material to be dried, said trays being arranged to permit passage of air through the tiers in a longitudinal direction only, means for circulating the air through the house, so that the air passes in opposite directions longitudinally through the two tiers, means for heating the air before it passes through the first tier and means for agitating the air 120 as it passes between the first tier and the second tier.

13. A drying apparatus comprising a house, two tiers of trays arranged side-by-side in said house for the material to be 130

- dried, said trays being arranged to permit passage of air through the tiers in a longitudinal direction only, means for circulating the air through the house, so that the 5 air passes in opposite directions longitudinally through the two tiers, means for heating the air whereby it tends to stratify and stationary means for agitating the air as it passes between the two tiers.
- 10 14. A drying apparatus comprising a house, a partition dividing the house into two compartments, a blower for circulating air through the two compartments successively, a tier of trays for the material to be dried arranged in each compartment, said trays being arranged to permit passage of air through the tiers in parallel paths only, means for heating the circulated air and means for mixing the air after it is discharged from one tier and before it enters the other tier.
- 15 15. A drying apparatus comprising a house, a partition dividing the house into two compartments, a blower for circulating air through the two compartments successively, a tier of trays for the material to be dried arranged in each compartment, said trays being arranged to permit passage of air through the tiers in parallel paths only, 20 means for heating the circulated air and stationary air swirling means through which the air passes during its travel between the two tiers.
- 25 16. A drying apparatus comprising a house, a partition dividing the house into two elongated compartments, a blower receiving air from the end of one compartment and discharging it into the adjacent end of the other compartment, means in said 30 second compartment for heating the air, a tier of trays for the material to be dried arranged in each compartment, said compartments being in communication at their other ends and means adjacent said other end for mixing the circulating air.
- 35 17. A drying apparatus comprising a pair of compartments arranged side-by-side means for blowing air longitudinally through the two compartments in series, 40 means for heating the circulated air, a tier of trays for the material to be dried arranged in each compartment, the trays being arranged to permit passage of the air through the tiers in a longitudinal direction only whereby the air passes through the two 45 tiers successively.
- 50 18. A drying apparatus comprising a pair of compartments arranged side-by-side, means for blowing air longitudinally through the two compartments in series, 55 means for heating the circulated air, a tier of trays for the material to be dried arranged in each compartment, the trays being
- arranged to permit passage of air through the tiers in a longitudinal direction only 60 whereby the air passes through the two tiers successively, and stationary means arranged to agitate the air after it passes through the first tier and before it reaches the second tier.
- 65 19. A drying apparatus comprising a house, a partition wall dividing the house into two compartments, means for circulating air through the two compartments in series, means for heating the air, a tier of 70 trays for the material to be dried adapted to be disposed in each compartment and means for reversing the tiers whereby the air passes through the tiers in opposite directions with respect to the trays.
- 75 20. A drying apparatus comprising a house, a partition wall dividing the house into two compartments, means for circulating air through the two compartments in series, means for heating the air, a tier of 80 trays for the material to be dried adapted to be disposed in each compartment and a turntable associated with each compartment for turning the tiers of trays to reverse the direction of the air therethrough with respect to the trays.
- 85 21. A drying apparatus comprising a house, a partition wall dividing the house into two compartments, means for circulating air through the two compartments in series, means for heating the air, a tier of 90 trays for the material to be dried adapted to be disposed in each compartment and a turntable in each compartment for receiving the tiers of trays and means for closing the 95 joints between the walls of the house and the sides of the tiers.
- 100 22. A drying apparatus comprising a house, a partition wall dividing the house into two compartments, means for circulating air through the two compartments in series, means for heating the air, a tier of 105 trays for the material to be dried adapted to be disposed in each compartment, a turntable in each compartment for receiving the 110 tiers of trays and stationary means for swirling the air after it passes through one tier and before it enters the other tier.
- 115 23. A drying apparatus comprising a house, air moving means arranged at one end of the house only for moving air through the house and back to the air moving means, the air tending to stratify while moving thru the house, and means arranged at the opposite end of the house for agitating the 120 air and removing the strata therefrom.

In testimony whereof, we have hereunto set our hands.

CLAUDE REES.
CHARLES F. HINE.
